UNITED STATES PATENT OFFICE.

CHARLES A. HOLT, OF CAMBRIDGE, MASSACHUSETTS, ASSIGNOR TO UNION INDUSTRIAL COMPANY, OF BOSTON, MASSACHUSETTS, A CORPORATION OF MAINE.

SPINNING RING.

1,423,216.

Specification of Letters Patent. Patented July 18, 1922.

Application filed June 8, 1921. Serial No. 476,069.

To all whom it may concern:

Be it known that I, CHARLES A. HOLT, a citizen of the United States, and resident of Cambridge, county of Middlesex, State of Massachusetts, have invented an Improvement in Spinning Rings, of which the following description, in connection with the accompanying drawing, is a specification, like characters on the drawing representing like parts.

This invention relates to spinning rings of the type exemplified by United States Patents No. 957,759, May 10, 1910 and No. 1,333,072, March 9, 1920 and one object of the invention is to provide an improved spinning ring of this type which is constructed so as to reduce the friction on the traveller when the ring is started up thereby enabling fine yarns to be spun without danger of breaking when the spinning frame is set in operation.

In order to give an understanding of my invention I have illustrated in the drawings a selected embodiment thereof which will now be described after which the novel features will be pointed out in the appended claims.

Fig. 1 is a plan view of a spinning ring embodying my invention.

Fig. 2 is a plan view of the under member of the casing.

Fig. 3 is an enlarged section on the line 3-3, Fig. 1.

Fig. 4 is an enlarged section on the line 4-4, Fig. 2.

Fig. 5 is a fragmentary view showing a modification.

The spinning ring comprises a metal casing formed of the under member 1 and upper member 2 which are detachably secured together and a lining member 3 of self-lubricating material, such for instance, as wood treated in oil, which is enclosed between the upper and under members 1 and 2 of the casing and is provided with the annular traveller-receiving recesses 4 in which the annular traveller 5 operates, said traveller having the upstanding stem 6 terminating in the guide eye 7.

The above described parts are such as are usually found in spinning rings of this type.

In this spinning ring the under member 1 is provided with the annular flange 8 on which the liner rests and the inner edge of said flange is bent upwardly as shown at 9

to form a support for the traveller when the spinning ring is idle. When the spinning ring starts up the rotation of the bobbin is communicated through the yarn to the traveller and the latter is rotated in its recess 60 with a gradually increasing speed until the desired speed has been reached.

When the ring is started up there will, of course, be more or less friction developed between the traveller and the supporting flange 9 but after the traveller is rotating at its operating speed it will be practically floating in the chamber 4.

In order to reduce the friction to which the traveller is subjected when it is being started up I propose to make the support 9 in the form of separated supporting portions which are spaced from each other by the spaces 10 and I propose further to upset the ends of each supporting portion 9 as 75 shown at 11 thereby to form separated points of support for the traveller. These upset portions 11 are provided with flat supporting surfaces 12 on which the ring rests, each supporting surface 12 having a relatively short dimension in the circumferential length of the traveller. With this arrangement the traveller is supported at a plurality of points by the portions 11 and the friction to which the traveller is subjected while it is being set in operation will be considerably less than if the traveller rested on a continuous supporting flange.

In Figs. 2 and 4 the support 9 is cut away at intervals as shown at 10 thus leaving arms 90 9 which are provided at each edge with the supporting surfaces 12. In Fig. 5 I have shown a construction wherein each portion 9 is also cut away between its edges thus leaving simply the portions 11 having the 95 raised surfaces 12. In both constructions the traveller is supported on separated supporting surfaces thus materially reducing the friction to which the traveller is subjected when the spinning frame is started up. 100

I claim.

1. In a spinning ring, the combination with a casing comprising separable under and upper members, of a lining member of self-lubricating material confined within 105 said casing and provided with an annular traveller-receiving chamber, and an annular traveller in said chamber, said under member of the casing having separated portions projecting inwardly beyond the outer wall 110

2
of said chamber to constitute a support for the traveller.

2. In a spinning ring, the combination with a casing comprising separable under 5 and upper members, of a lining member of self - lubricating material confined within said casing and provided with an annular traveller-receiving chamber, and an annular traveller in said chamber, said under member of the casing having separated portions 10

projecting inwardly beyond the outer wall of said chamber to constitute a support for the traveller, the edges of each projecting portion being upset to form relatively narrow separated supporting surfaces for the 15 traveller.

In testimony whereof, I have signed my name to this specification.

CHARLES A. HOLT.
